DESIGN FOR A CHAIR OR SIMILAR ARTICLE

Lewis Larsen, Menominee, Mich., assignor to Heywood-Wakefield Company, Gardner, Mass.,
a corporation of Massachusetts

Application August 8, 1936, Serial No. 64,299

Term of patent 3½ years

To all whom it may concern:

Be it known, that I, Lewis Larsen, a citizen of the United States and a resident of Menominee, county of Menominee and State of Michigan, have invented a new, original, and ornamental Design for a Chair or Similar Articles, of which the following is a specification, reference being had to the accompanying drawing, forming a part thereof, in which the figure is a perspective view of a chair or similar article showing my new design.

I claim:

The ornamental design for a chair or similar article substantially as shown.

LEWIS LARSEN.
